HALFDAN ASPER, OF PITTSBURGH, PENNSYLVANIA.

DOOR ARRANGEMENT FOR DUMP-CARS.

1,076,860.

Specification of Letters Patent.

Patented Oct. 28, 1913.

Application filed April 21, 1910. Serial No. 556,701.

To all whom it may concern:

Be it known that I, HALFDAN ASPER, a resident of Pittsburgh, in the county of Allegheny and State of Pennsylvania, have 5 invented a new and useful Improvement in Door Arrangements for Dump - Cars, of which the following is a specification.

This invention relates to door operating mechanism for railway cars, and more especially to mechanism for operating horizontal drop doors for gondola and similar cars.

The invention relates to that type of door operating mechanism wherein the door is held in closed position by means independent of the lifting connection so as to relieve the latter from heavy strains.

The object of the invention is to simplify this type of door and door operating mechanism and to render the same easier to operate than with prior mechanisms of the same general type.

This invention comprises, generally stated, a lifting shaft connected to a bodily movable door, and inter-engaging connections between the shaft and door whereby as the door approaches the limit of its closing movement it is bodily moved to bring its edge portion above the lifting shaft or means connected therewith, so as to derive 30 support from said shaft.

In the accompanying drawings Figure 1 is a plan view showing a portion of the car bottom with my invention applied thereto; Fig. 2 is a side view of the door and door 35 operating mechanism; Fig. 3 is a vertical section taken on the line 3—3, Fig. 1; Fig. 4 is a cross section through the car and door showing the door in closed position; Fig. 5 is a similar view showing the door during 40 the first stages of its opening movement; Fig. 6 is a similar view showing the door open; Fig. 7 is a detail view showing means for operating the lifting shaft; and Fig. 8 is a detail sectional view indicating a modification.

The drawings show a portion of an all metal gondola car provided with drop doors and to which the invention is applied but it is obvious that the invention can be applied to various forms of cars. Only a small portion of the car frame is shown, the illustrated portion including center sill 1, cross bearers or transoms 2, a portion of the car side 3, provided with a lower chord in the 55 form of a Z-bar 4, and stakes 5. As illustrated, the center sills are covered by longi-

tudinal plate 6, and the cross bearers or transoms by plates 7 extending outwardly to the Z-bar 4, thus providing rectangular door openings. The edges of the plates 6 and 7 are turned downwardly somewhat as shown at 8 and 9 respectively, to a depth corresponding to the inner vertical flange 10 of the Z-bar 4, thereby forming shallow pockets at the door openings.

The door 11 may be formed of any suitable metallic construction, being shown in the form of a plate provided with flanges 11^a and 14 on three edges, and an angle bar 11^b on the fourth edge to stiffen and strengthen the same. The inner edge of the door is mounted so that it is practically pivoted or hinged but so as to permit its bodily movement. This is accomplished by supporting the door upon brackets 12 secured to the center sill and projecting outwardly and then turned upwardly and carrying the door supporting rollers 13 in order to reduce friction.

The inner flange 14 of the door serves as 80 a stop to prevent the door being pulled entirely off the supporting rollers and is curved to conform to the contour of the rollers 13. Wear plates 15 are preferably provided for contact with the rollers 13, said plates being 85 riveted to the door and having their inner ends curved downwardly, as shown, to conform to the contour of the flange 14 and rollers 13. Said wear plates are provided with ribs 16 at the ends of the rollers to 90 serve as guides and prevent side motion of the door.

Located underneath the web of Z-bar 4 is the lifting shaft 17 which may be connected to the outer edge of the door by any 95 suitable means capable of raising the outer edge of the door when the shaft is rotated in the proper direction. This lifting means is shown as a chain or chains 18, one such chain being shown, but obviously any 100 greater number may be employed. The outer end of this chain is secured and adapted to wind on a spool 19 on the shaft 17, and its inner end is adjustably secured to the door. The connection shown comprises 105 a casting 20 riveted to the door and having a web or flange 21 provided with an opening through which extends a threaded eye bolt 22 on the end of chain 18, said eye bolt receiving adjusting nuts 23 on opposite sides 110 of the flange or web 21. Outside of the connection of the chain to the casting 20 said

- casting is provided with a downwardly projecting portion 24 which extends below the point of connection of the chain with said casting and which is adapted to abut against the chain and serve as a strut to insure the outer edge of the door being lifted sufficiently high in case the chain should show any tendency to sag.
- The means for bodily moving the door to bring its upper edge above the winding shaft so as to receive support therefrom comprises one or more gears 26 secured to the shaft and arranged to engage toothed segments 27 secured to the lower face of the door at the outer edge thereof, said toothed segments being so formed that when the door approaches the limit of its closing movement the teeth of said segments inter-engage with the teeth of gears 26 so that in the further rotation of the gears 26 the outer edge of the door is lifted to closed position and the door drawn bodily outwardly from the position shown in Fig. 5 to that shown in Fig. 4, so that the door in its closed position is supported directly by the shaft 17. Preferably the point of supporting contact between the segments 27 and the gears 26 when the door is fully closed is not directly above the center of shaft 17, but somewhat inside the same, such as at 28, Fig. 4, thereby giving a slight lever arm upon which the weight of the door and load acts and tending to rotate shaft 17 to permit the doors to open. This lever arm can be so proportioned that the weight on the door acting thereon will practically overcome or balance the frictional resistance to the bodily movement of the door, so that in opening the door no great amount of power need be applied to the winding shaft. Preferably the pitch line 29 of the spool 19 on which the chain 18 winds is slightly less in diameter than the pitch line 29^a (Fig. 6) of gears 26, so that in the final closing movement of the door, that is, during the time that the gears and toothed segments inter-engage the chain will be slightly slackened, thereby entirely relieving the same of strain and also preventing binding of the parts, as would otherwise occur in case the chain was wound on a spool whose pitch line was slightly larger than the pitch line of the gears 26.
- To hold the shaft 17 against accidental backward rotation when the doors are closed, any suitable means may be employed, such as shown in Fig. 7, where said shaft is shown as provided with a ratchet wheel 30 which is engaged by pivoted locking dog or pawl 31. This figure also shows one means for rotating said shaft, such means comprising a lever 32, provided with a reversible pawl 33 for engaging the ratchet wheel 30 so that thereby the shaft may be positively rotated in either direction. Shaft 17 is mounted in bearings 35, said bearings be-

ing formed directly in castings 36, which serve as connectors between the under frame and car sides, being shown as riveted to the outer ends of the cross bearers or transoms 2, and the web of the Z-bar 4, and in turn having the lower ends of the stakes 5 riveted to their outer edges. Some connector is essential for uniting the under frame and car sides, and by forming this connection as a casting which is provided with bearings for the winding shaft the structure is materially simplified and cheapened, making it unnecessary to provide separate bearings for the winding shaft.

The toothed segments 27 preferably will be so formed that the outer edge of the door is lifted into tight engagement with the lower edge of the flange 10 of the Z-bar 4 at the door opening, so as to prevent the escape of fine lading at this point. At the inner edge of the door it is advisable to leave a slight clearance between the door and the lower edges of the door opening flange 8, but this need be only very slight. If it is desired to have an absolutely tight joint at this place the wearing plates 15 which rest upon rollers 13 may be made somewhat wedge shaped, or having inclined lower faces, as shown at 37, Fig. 8, so that as the door is pulled outwardly in the final closing movement its inner edge is lifted into tight engagement with the lower edge of the door opening flange. The operation of the door mechanism is as follows: When the door is open the parts will be in the position shown in Fig. 6, with the inner edge of the door suspended on the rollers 13, and the outer edge suspended by the chains 18. The rotation of shaft 17 in the direction of the arrow causes the chain to be wound up on spool 19, thereby lifting the outer edge of the door, said door swinging on the rollers 13 practically as on a pivot. As the door approaches the horizontal position the tension of the chain moves the door bodily inwardly, that is, toward the center line of the car, to somewhat the position shown in Fig. 5, said door rolling with very little friction on the rollers 13. The gears 26 then engage with the rack segments 27, completing the inward movement of the door, if necessary, and lifting the outer edge of the door still higher, and, finally through the inter-engaging teeth, drawing the door bodily outwardly, until it is completely closed or brought to the position shown in Fig. 4. During the latter part of the movement the chains become somewhat slack, due to the lesser diameter of the pitch line of spool 19 as compared with the pitch line of the gears 26. The winding shaft is then locked against accidental rotation and the doors are supported in closed position by the rollers 13 and shaft 17, entirely relieving the chains from strain. To open the door the shaft 17 is released and

rotated slightly in the backward direction. This causes the door 11 to be pushed bodily toward the center line of the car, but since the actual point of support of the door is 5 not directly above the center of the shaft the weight on the door acting on this short lever arm assists in causing the shaft 17 to rotate, so that very little power is required to overcome the friction of the load on the door.

10 As soon as the door has reached the position shown in Fig. 5 it will drop by gravity to fully open position.

The door mechanism described comprises a minimum number of parts and is therefore 15 economical of construction and application. All parts are of simple construction and de-arrangement is therefore practically impossible. The door is positively locked in closed position so that there is no danger of accidental discharge of the load on account of 20 failure of the winding chains or their connections. All of the operating mechanism is located within the outer faces of the car sides and is therefore protected from injury 25 and also permits a maximum width of car body.

While the drawings illustrate only a single door, it will be understood that any number of doors may be operated from the same 30 shaft. These doors may be arranged for practically the entire length of the car, or any other desired amount of floor opening may be provided.

While the invention has been shown applied to horizontal doors mounted to swing on an axis extending longitudinally of the car it is apparent that the same arrangement can be used with inclined doors, or doors mounted to swing on an axis extending 35 transversely of the car, the lifting shaft in the latter case also extending transversely of the car. Instead of having the door arranged to swing downwardly at its outer edge the reverse arrangement may be used 40 to provide a center discharge opening. Furthermore, while the door is shown as supported by gears on a winding shaft, it may be supported by any suitable stationary support, such as a bracket or brackets secured 45 to the car body.

50 What I claim is:

1. Car door mechanism comprising in combination with a door, a rolling support for one edge of the door, a lifting shaft, and 55 connections therefrom to the opposite edge of the door and arranged at the end of the closing movement to move said door bodily to bring its free edge over a support adjacent the door opening.

60 2. Car door mechanism comprising in

combination with a door, a rolling support for one edge of the door, a lifting shaft, flexible connections therefrom to the door, and inter-engaging rack and gear connections between the shaft and door and arranged on the closing movement of the door to move said door bodily to bring its free edge over a support adjacent the door opening.

3. Car door mechanism comprising in 70 combination with a door, a rolling support for one edge of the door, a winding shaft, flexible connections therefrom to the door, a toothed segment on the door, and a gear on the shaft arranged to engage said toothed 75 segment at the end of the closing movement and move the door bodily.

4. Car door mechanism comprising in combination with a swinging bodily movable door, a winding shaft, flexible connections therefrom to the door, and independent means actuated from said shaft for moving and supporting the door in closed position from the shaft, said parts being arranged to cause the flexible connections to 80 become slack when the door is fully closed.

5. Car door mechanism comprising in combination with a swinging bodily movable door, a lifting shaft, a spool or drum thereon, a chain connecting the same with 85 the door, a gear on the shaft, and a rack member on the door arranged to be engaged by said gear on the final closing movement of the door and move the same to support said door on the shaft, the pitch line of said 90 drum being less than the pitch line of said gear, whereby the chain becomes slack when the door is fully closed.

6. Car door mechanism comprising in combination with a swinging bodily movable door, a lifting shaft, flexible connections therefrom to the door, a gear on said shaft, and a segmental toothed member on the door arranged to be engaged by said gear on the final closing movement and 100 through the same support the free edge of the door, said gear and toothed member being so arranged that when the door is in its fully closed position the point of support is at one side of the vertical line through 105 the center of said shaft, whereby gravity will assist in rotating said shaft in the opening movement of the door.

In testimony whereof, I have hereunto set my hand.

HALFDAN ASPER.
